COLLAR

Lajos Bihaly, London, England

Application December 16, 1950, Serial No. 201,165

2 Claims. (Cl. 2—129)

It has been proposed to simplify and improve the mass production of garments or garment-parts where close adherence to a pattern is required, by securing the fabric layers constituting these garments or garment-parts in a suitable frame and guiding the assembly by pre-set mechanical means under the needle of a sewing machine.

One such method and apparatus has been described in detail in our co-pending application Ser. No. 201,106 filed December 16, 1950, now Patent No. 2,684,651 while others have been proposed.

One of the difficulties appearing when stitching according to some of these methods is connected with the production of sharp corners, for example, those which are called "points" in collar-making, because they are required to form the pointed ends of a collar.

This difficulty is due to the fact that the frame holding the fabric layers is usually guided in such a way as to cause the frame to move, and thus the stitch to run, in a variable direction. For example, the frame can move from right to left at a given moment, while it can move from front to back at another. Thus, it is difficult to support the fabric assembly in such a way as to compensate for the pull of the stitch coming from varying directions.

Further, some of the methods possible for the mechanical guidance of fabric assemblies under the needle of a sewing machine are such that they make it altogether impossible or very difficult to produce sharp points, for example, if the frame is guided by pins along channels cut to the exact shape of the stitch to be produced, in which case jamming at sharp corners is likely to take place.

According to the present invention, this difficulty in the production of sharp corners by automatically-guided stitching is obviated by continuing the line of stitching beyond the apex point of the corners and returning to this point in a small loop, arriving in the right direction for steady continuance along the other limb of the corner.

The additional small loop thus formed can, if necessary, be removed subsequently, but, for example, in the case of a collar point, it falls into the turned-in seam and can be disregarded in subsequent operations.

The attached drawing shows the application of the method according to the invention in connection with method and apparatus described in our co-pending application Ser. No. 201,106 filed December 16, 1950, now Patent No. 2,684,651.

The constituent plies A of such a collar are secured in frame 1 by clamp 2. Frame 1 is positioned in the apparatus by means of locating elements 3, as more fully described in the aforementioned application. The line

2

of stitching B realised with the apparatus comprises at both collar points small loops C formed by the continuation of the line of stitching past the apex point and by a small loop connecting the two continuation lines.

Once the collar assembly is turned inside out, the loops C are hidden between the outer plies.

In the example shown, the whole seam comprises 350 stitches distributed in such a way as to make the stitch length appreciably shorter at the places where the line of stitch is curved sharply, and longer where this line is straight or nearly straight, as shown by a comparison of the parts between 0° and 110° on the one hand with those between 110° and 250° on the other. This is achieved by appropriate shaping of the cams or equivalent controlling means of the apparatus guiding the workpiece under the needle as described in application Serial No. 201,106 filed December 16, 1950, now Patent No. 2,684,651. As a result, the angle produced by any two consecutive stitches will deviate as little as possible from 180° and the pull of the second stitch will be taken up practically fully by the anchorage provided by the first stitch.

I claim:

1. A collar comprising in combination: at least two constituent plies superposed to each other, said collar having a contour comprising longitudinal outer and inner border lines and two transverse border lines, said transverse border lines forming equal predetermined angles with said outer longitudinal border line to define the tips of the collar; each of said plies having an area slightly greater than that of the collar and defined by border lines extending substantially parallel to the contour of the collar so that the area of each of said plies is greater than the area of the collar by a narrow marginal zone of uniform width; stitchings connecting said superposed plies with each other, said stitchings forming a line extending from a point on one of said transverse border lines near said inner longitudinal border line along said transverse border line to the collar tip formed at the meeting point between said transverse border line and said outer longitudinal border line, then, as a continuation of said transverse border line, beyond said tip into said marginal zone, then in a small loop back to said tip, and from there along said longitudinal outer border line to the second collar tip formed at the meeting point between the other transverse border line and said outer longitudinal border line, then as a continuation of said longitudinal outer border line beyond said second collar tip into said marginal zone, then in a small loop back to said second tip, and from there along said other transverse border line to a point on said other transverse border line near said inner longitudinal border line, said marginal zones on each of said plies being folded inwardly such as to be disposed between those areas of the outside plies of the collar which on three sides are surrounded by said line of stitchings.

2. A collar as claimed in claim 1, in which the stitch length is shorter in the loop than in the remaining portions of the line of stitching.
